US0D1106441S

(12) **United States Design Patent** (10) **Patent No.:** **US D1,106,441 S**
(45) **Date of Patent:** **** Dec. 16, 2025**

(54) **REGULATOR VALVE FOR A BREATHING APPARATUS**

(71) Applicant: **Dräger Safety AG & Co. KGaA**, Lübeck (DE)

(72) Inventor: **Jason Allan**, Blyth (GB)

(73) Assignee: **Dräger Safety AG & Co. KGaA**, Lübeck (DE)

(**) Term: **15 Years**

(21) Appl. No.: **29/915,590**

(22) Filed: **Nov. 1, 2023**

(30) **Foreign Application Priority Data**

May 4, 2023 (GB) 6280114

(51) **LOC (15) Cl.** **29-02**

(52) **U.S. Cl.**

USPC **D24/110.6**

(57) **CLAIM**

The ornamental design for a regulator valve for a breathing apparatus as shown and described.

DESCRIPTION

FIG. 1 is a front perspective view of a regulator valve for a breathing apparatus showing my new design;

FIG. 2 is a rear perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines depict portions of the regulator valve for a breathing apparatus that forms no part of the claimed design.

1 Claim, 8 Drawing Sheets
